UNITED STATES PATENT OFFICE.

ISAAC SIMPSON, OF EDGEWOOD PARK, PENNSYLVANIA, ASSIGNOR, BY DIRECT AND MESNE ASSIGNMENTS, TO THE WESTINGHOUSE AIR BRAKE COMPANY, OF PITTSBURGH, PENNSYLVANIA, A CORPORATION OF PENNSYLVANIA.

FRICITION DRAFT AND BUFFING MECHANISM.

1,036,920.

Specification of Letters Patent. Patented Aug. 27, 1912.

Application filed August 19, 1908. Serial No. 449,284.

To all whom it may concern:

Be it known that I, ISAAC SIMPSON, a resident of Edgewood Park, in the county of Allegheny and State of Pennsylvania, have invented a new and useful Improvement 5 in Friction Draft and Buffing Mechanism, of which the following is a specification.

This invention relates to friction draft 10 and buffing mechanism, and particularly to friction draft gears for railway cars.

The object of the invention is to provide mechanism of the character specified, which is of very simple construction, which is durable, which develops a large capacity under 15 buffing and draft strains, and which releases with certainty and ease after compression.

With the above objects in view, the invention comprises the construction and arrangement of parts hereinafter described 20 and claimed.

In the accompanying drawings, Figure 1 is a horizontal sectional view of the improved friction mechanism, showing a portion 25 of the draft sills of a railway car and a portion of the draw bar; Fig. 2 is a transverse section on the line $x-x$, Fig. 1; Fig. 3 is a front end view of the friction mechanism, the front follower plate being omitted; Fig. 4 is a longitudinal section showing a 30 slight modification of the friction mechanism; Fig. 5 is a front end view of the housing; and Figs. 6 and 7 are perspective views respectively of the wedge block and the inner friction member or blocks.

In the drawings, the center or draft sills of the car are shown at 1.

2 designates the usual draw-bar, to one end of which is secured the usual yoke or 40 strap 3.

4 and 5 designate respectively the front and rear follower plates, mounted within said yoke and adapted to bear against the two pairs of draft lugs 6 and 7, all as is 45 usual in friction draft mechanism.

Within the yoke 3, is the housing 8, which is of substantially rectangular shape, as shown in Figs. 2 and 3, with curved side faces and substantially flat top and bottom 50 faces. The rear end of the housing is partly closed by a transverse plate 15, whose side edges are flanged as at 14, to stiffen the

same. Within the housing are the posterior springs 9 and 10, one of which surrounds the other, and one of which is preferably 55 considerably larger than the other, as shown. These springs at their forward ends, bear against a division plate or partition 11, and at their opposite ends bear against the transverse plate 15. The rear 60 ends of these springs, are held in proper position or centered by means of a boss 17, punched out of the plate 15, and entering the end of the spring 10. The forward ends of these springs are held in proper position 65 by means of semi-cylindrical flanges 18, on the inner friction blocks or members 16. The partition plate 11, is seated against inwardly projecting flanges 19, on the friction blocks 16, and the flanges 18, project 70 rearwardly sufficiently far to inclose the ends of the springs 9 and 10.

In the forward end of the housing are located the two outside or stationary friction members or blocks 20, which as shown in 75 Fig. 2, fit snugly against the side walls of the housing and are held against longitudinal movement in the housing by means of lugs 21, on said blocks entering holes in the housing. The inner faces of these friction 80 blocks are slightly tapered, as shown in Fig. 1. The inside friction blocks or members 16, have their outer faces correspondingly tapered and coöperate with the outer friction members to produce the necessary friction 85 in the operation of the gear.

In order to create the necessary friction between the blocks 16 and 20, suitable means are provided for spreading the blocks 16, or forcing the same outwardly against blocks 90 20. The spreading means illustrated comprises a pair of wedge blocks 13, provided with inclined faces 22, coöperating with similar inclined faces 23, on the inner friction members 16. The wedge blocks 13, 95 have their inner faces formed substantially semi-cylindrically, as at 24, Fig. 6 and inclose or surround the anterior spring 12. Said wedge blocks at their rear ends are provided with inwardly projecting flanges 100 25, against which the end of the spring 12, bears. The spring 12, may be either slightly shorter than the wedge blocks 13, as shown in Fig. 1, so that it is not acted on by the

front follower plates, or may be slightly longer than said wedge blocks as shown in Fig. 4, so as to give a preliminary action before the wedge blocks and friction plates are put into action.

6 In the modification shown in Fig. 4, the preliminary action of the spring 12, is resisted by the slight friction on the outside of the coils of said springs, due to the fact 10 that the pressure of said spring against the flanges 25, tends to force the wedge blocks 13, rearwardly and the beveled faces on the wedge blocks and inner friction blocks force the wedge blocks toward the axis of the 15 gear and against the outside of the coils of the spring 12. This friction on the outside of the coils gives a suitable capacity in the preliminary action of the gear with a slight recoil. In this modification the front fol- 20 lower plate may contact first with either the wedge blocks 13, or inner friction blocks 16, while in Fig. 1 the wedge blocks 13, are always in contact with the follower plate during the inner travel of the gear, al- 25 though the friction blocks 16, may also contact with the follower plate. This is gov- 30 erned by the strength of the spring 12. Preferably this spring is made strong enough, and the distance between the fol- 35 lower plate and the ends of the friction blocks 16, is such, that said follower plate does not contact with said friction blocks at any time.

35 The inner faces of the inner friction blocks 16, are recessed and ribbed as shown in Fig. 7, in order to give the necessary strength with minimum weight. These friction blocks are provided with the side flanges 26, between which the wedge blocks 40 are seated. It is the usual practice, when the friction blocks and the co-acting friction plates are of different relative degrees of hardness, to make the friction plates, corresponding to the plates 20, of a comparatively soft metal, such as malleable iron, and the inner friction blocks, corresponding to the blocks 16, of a harder metal, such as chilled cast iron or steel. The latter metal is, of course, more brittle than the former, 45 and frequently the harder blocks break. In my friction mechanism, the inner friction blocks or members 16, are made of the softer metal, and the outer friction plates or members 20, of the harder or more brittle metal. 50 The latter fit closely against the side walls of the housing, and are backed and reinforced over their entire outer surfaces so that breakage is practically impossible, even though the outer plates be made of very brit- 55 tle metal.

60 The housing 8, shown in the drawings is formed of metal, such as from a section of wrought iron or steel tubing. The walls are shown of uniform thickness from end to end 65 and the transverse plate 15, is suitably se-

cured to said walls as by welding the same thereto. The wrought metal housing gives maximum strength with minimum weight, and is much more reliable than the cast housings in general use.

70 In operation, the stresses tending to shorten the gear tend to force the wedge blocks 13, toward the rear, but by reason of the inclined faces 22 and 23, on said wedge blocks and inner friction blocks respectively, 75 the latter are also forced toward the rear, sliding on the inclined or tapered faces of the outer friction blocks. The rearward travel of the inner friction blocks along such inclined faces causes the inner friction blocks 80 to move inwardly, that is, toward the axis of the gear, and force the friction mechanism into a more circumscribed area. This movement of the whole friction mechanism into a more circumscribed area within the 85 outer friction plates causes a tendency of the wedge blocks 13, and friction blocks 16, to move apart longitudinally, which, of course, 90 would cause an outward movement from each other on their bevels. But as the pressure at the bevels of said blocks is transmitted toward the axis of the friction mechanism, said pressure is resisted radially or centrifugally by the anterior spring 12, which radial action provides space to ac- 95 commodate the parts, thereby compensating, or may be made to more than compensate, according to the strength of anterior spring 12, the more circumscribed area within the outer friction plates into which the friction 100 mechanism is being compressed. This completely eliminates the outward movement from each other of the wedge blocks 13, and the friction blocks 16, and allows the spring 12, to be compressed without any movement 105 outwardly upon each other of the bevels of friction blocks 16, and wedge blocks 13. The strength and resistance of this spring 12, determines the amount of pressure existing between the friction blocks or members. 110 The posterior springs, of course, are compressed under the inward and rearward movement of the inner friction blocks. As soon as the friction mechanism is relieved from the pressure which shortens the same, 115 the first action is for the spring 12, to expand radially or centrifugally, thus tending to force the wedge blocks 13, radially or outwardly, and by reason of the wedge faces between said blocks and the inner friction 120 blocks, this force is expended in causing the wedge blocks to move forwardly or in a direction to lengthen the friction mechanism. Consequently the pressure of the inner friction blocks is instantly and certainly re- 125 leased, so that the posterior springs 9, and 10, need merely push the inner friction blocks forwardly, and this action occurs gradually and easily. The bevels or wedge faces on the blocks 13 and 16 can be made 130

steep enough to give a very high capacity without any danger of sticking.

The friction mechanism described is composed of a minimum number of parts, all of 5 simple and strong construction. The mechanism is, therefore, cheap to manufacture, is very durable and strong, develops a high capacity of friction in the closing movement thereof and releases easily and with cer- 10 tainty.

What I claim is:

1. In friction draft and buffing mechanism, the combination with a casing, of co-operating inner and outer friction members 15 contained in said casing, a longitudinally arranged posterior spring acting against the inner friction members, spreading means acting on the inner friction members, and a longitudinally confined coiled spring in- 20 closed by said spreading means and acting radially on said spreading means.

2. In friction draft and buffing mechanism, the combination with a casing, of co-operating inner and outer friction members 25 mounted in said casing, a longitudinally arranged posterior spring acting against the inner friction members, wedge blocks ar- ranged to spread said inner friction mem- bers, and a longitudinally confined coiled 30 spring inclosed by said wedge blocks and acting radially on said wedge blocks.

3. In friction draft and buffing mechanism, the combination with a casing, of co-operating inner and outer friction members 35 mounted in said casing, a longitudinally ar- ranged posterior spring acting against the inner friction members, wedge blocks ar- ranged to spread said inner friction mem- bers and provided at their posterior ends 40 with inturned flanges, and a coiled spring

inclosed by said wedge blocks and bearing against the end flanges thereof.

4. In friction draft and buffing mechanism, the combination with a casing, of co-operating inner and outer friction members 45 mounted therein, a longitudinally arranged posterior spring seated against the ends of said inner friction members, wedge blocks acting directly against said inner friction members and acting to spread the same, and 50 a spring inclosed by and adapted to act radially on said wedge blocks.

5. In friction draft and buffing mechanism, the combination with a casing, of co-operating inner and outer friction members 55 mounted therein, flanges on the posterior ends of said inner friction members, a longitudinally arranged posterior spring acting on and having its end positioned by the flanges of said inner friction members, 60 spreading means acting on said inner friction members, and a coiled spring inclosed by said spreading means and acting radially to control the action thereof.

6. In a friction draft and buffing mecha- 65 nism, the combination with a casing having longitudinal friction faces and friction members having friction surfaces adapted to engage the friction faces of the casing, of wedge blocks for spreading the friction 70 members against the casing and a spring confined axially and longitudinally by said wedge blocks and adapted to act radially on said wedge blocks.

In testimony whereof, I have hereunto set 75 my hand.
